UNITED STATES PATENT OFFICE

WILLIAM J. DE WITT, OF AUBURN, MASSACHUSETTS, ASSIGNOR TO SHOE FORM CO., INC., OF AUBURN, NEW YORK, A CORPORATION OF NEW YORK

BACK-PART STAY

Application filed June 11, 1929. Serial No. 370,028.

This invention relates to an improvement in back part stay for shoe forms such as is shown for example in my copending application, Serial No. 265,000, filed March 27, 1928. 5 As shown in the copending application the back part stay is attached at its forward end to a toe form and bears at its rearward end against the heel counter of the shoe.

The primary object of the present invention is to provide a back part stay provided with a loop at its rearward end, which loop is so constructed that the body of the back part stay will bend freely upwardly and hold the toe form yieldingly in its position in the 15 shoe.

Another object of this invention is to provide a back part stay provided at its rearward end with a closed loop which is integral with the body of the stay and which is quickly and 20 easily formed and closed by following the present invention.

A further object of this invention is to provide a back part stay which is covered to a considerable extent with fabric of a color 25 chosen so that the stay will present a pleasing appearance when inserted in a shoe. Other objects of the invention will appear from consideration of the following specification taken in connection with the drawings, 30 in which:

Fig. 1 is a side elevation of a completed back part stay embodying this invention;

Fig. 2 is a similar view of a back part stay before the rearward loop has been completed;

Fig. 3 is a view illustrating one step in the preparation of the loop;

Fig. 4 is a sectional view taken along the line 4—4 of Fig. 3;

Fig. 5 is a sectional view taken substantially along the line 5—5 of Fig. 1 and illustrating the loop before the final operation is performed; and

Fig. 6 is a side elevation of a portion of a completed back part stay upon which fabric 45 has been applied.

The function and purpose of the back part stay to which this invention applies is clearly shown and set forth in my copending application above mentioned and also in my Patent No. 1,646,016, dated October 18, 1927. In

view of this disclosure it is believed unnecessary to illustrate the manner of using a shoe form provided with a back part stay or to show a form and back part stay inserted in a shoe.

The back part stay 10 is preferably made of celluloid or similar material in tubular form and in order to supplement the resiliency of the material forming the stay a thin length of wire 11 is usually inserted into the hollow of the tube. This wire 11 terminates short of the rear end of the tube and is provided at its front end with an integral loop 12. The wire and tube are assembled when both are in the straight extended position. 55 The rearward end of the tube and wire combined is then offset to form an incomplete loop 15 and the forward end of the wire 11 is provided with an integral loop 12. It will be noted that the end 16 of the loop 15 extends 60 across the body of the tube, as shown in Fig. 2, when the tube and wire are bent and that the wire 11 terminates at a considerable distance from the end of the tube. In order to complete the loop 15 it is necessary that the 65 end 16 be rigidly united to the body of the tube. 70

The preferred procedure to be followed in uniting these members is particularly shown in Figs. 3, 4 and 5 wherein it will be noted 75 that the end 16 is provided with a V-shaped notch 17 formed by subjecting it to an emery wheel 18 or similar cutting device. After the notch 17 has been formed the end 16 is drawn back until it passes the body of the 80 tube 10 and is then released the notch 17 receiving the body of the tube 10 and by reason of its form holding the end 16 in position without need of particular attention. Other means for forming the notch 17 may be employed and such notch need not necessarily be V-shaped. This feature of the invention is preferably that the end 16 shall be so treated that it has a secure engagement with the body of the tube such that it will automatically remain in contact therewith. The end 16 is then treated with acetone or similar adhesive and is quickly welded or rigidly 85 united to the body of the tube. 90

While the tube 10 may be made of any de- 100

sired material and of any color it has been found that in many instances the celluloid of the back part stay can not supply the color, which will correspond to or form a pleasing contrast to the color of the shoe in which the shoe form including the back part stay is to be inserted. Accordingly the body of the back part stay is covered with a fabric 20 of the desired color which is preferably tubular and slipped over the body of the tube before the end 16 is secured thereto. The acetone or other adhesive by which the end 16 is secured to the body 10 will function equally well even if the fabric 20 is in place. In place of so securing the fabric 20 it may be attached directly to the stay tube by touching the end or any part of it with acetone or a similar adhesive so that it will be readily fixed in place.

It has been found particularly desirable to dress the shoe by covering the stay with a shoe lacing of the same color as the lacings used in the shoe. It will be noted that the loop 15 is offset from the main body portion of the tube which is unbent and that the end 16 of the loop tends to direct the tube upward directly away from the heel counter. The loop 12 is similarly offset and consequently the back part stay forms a smoothly continuous curve from the toe to the heel counter.

While I have described one form of tube and one method of completing the loop 15 I am not limited thereto since other improvements might be made without departing from the spirit and scope of this invention as set forth in the following claims.

I claim:

1. A back part stay for a shoe form comprising a tube of celluloid or similar material, and a resilient wire inserted into the hollow of the tube, one end of the wire projecting from the tube while the other end is encased, the ends of the back stay being formed into loops both offset from the body of the stay in the same direction.

2. A back part stay for a shoe form comprising a tube of celluloid or similar material, and a resilient wire inserted into the hollow of the tube, said tube terminating at its outer end in a loop offset from the body of the tube, the end of the loop being rigidly united to the body of the tube.

3. A back part stay for a shoe form comprising a tube of celluloid or similar material, and a resilient wire inserted into the hollow of the tube terminating at its outer end in a loop offset from the body of the tube, the end of the loop being provided with a depression which receives the body of the tube thus yieldingly holding the parts in contact.

4. A back part stay for a shoe form comprising a tube of celluloid or similar material, and a resilient wire inserted into the

hollow of the tube terminating at its outer end in a loop offset from the body of the tube, the end of the loop being provided with a V-shaped notch which receives the body of the tube thus yieldingly holding the parts in contact. 70

5. A back part stay for a shoe form comprising a tube of celluloid or similar material, and a resilient wire inserted into the hollow of the tube, said tube terminating at its outer end in a loop offset from the body of the tube and a fabric covering the body of the tube and firmly attached thereto at said loop. 75

6. The method of forming a loop at the end of a back part stay for shoe forms which stay includes a tube of celluloid comprising the following steps, bending the portion of the tube to form the loop so that the end extends across the body of the tube, forming a depression in the end, assembling the end with the body of the tube, the latter resting in the depression and uniting the contacting surfaces by adhesive. 85

Signed by me at Auburn, N. Y., this 7th day of June, 1929.

WILLIAM J. DE WITT.
